BOX FOR A PORTABLE MOTOR OR THE LIKE

Arnold M. Thompson, Wheaton, Ill., assignor to Thompson Designs, Inc., Franklin Park, Ill., a corporation of Illinois

Filed Oct. 11, 1962, Ser. No. 72,068

Term of patent 14 years

(Cl. D58—11)

Fig. 1.

Fig. 2.

FIG. 1 is a top plan view of a box for a portable motor or the like embodying my new design; and

FIG. 2 is a side view thereof.

The bottom of the illustrated box is plain and unornamented.

The dominant features of my design reside in the portions shown in full lines.

I claim:

The ornamental design for a box for a portable motor or the like, substantially as shown and described.
